UNITED STATES PATENT OFFICE.

JOHN H. GARTNER, OF POCATELLO, IDAHO.

TRANSOM-LIFTER.

1,042,906.

Specification of Letters Patent.

Patented Oct. 29, 1912.

Application filed May 11, 1912. Serial No. 696,623.

To all whom it may concern:

Be it known that I, JOHN H. GARTNER, a subject of the Emperor of Austria-Hungary, and a resident of Pocatello, in the county of 5 Bannock and State of Idaho, have invented an Improvement in Transom-Lifters, of which the following is a specification.

In my invention a vertically slidable rod is employed as in a common and well known 10 variety of transom-lifters, but the upper end of the same is connected with the transom proper by means of a spring, which is held slidably in a curved guide attached to the door casing; and the rod is operated, 15 that is to say, adjusted vertically, and locked in any position, by improved means.

The details of construction, arrangement, and operation of the invention are as hereinafter described, and illustrated in the accompanying drawings, in which—

Figure 1 is a face view of a door and transom showing my invention applied. Fig. 2 is a side view of the same. Fig. 3 is an enlarged section of the invention including a portion of the door casing. Fig. 4 is 25 a perspective view of a curved guide for the spring which connects the sliding rod with the transom proper. Fig. 5 is a cross section on the line 5—5 of Fig. 3. Fig. 6 is a perspective view of certain elements of the mechanism employed for adjusting the 30 slid-able rod. Fig. 7 is a cross section on the line 7—7 of Fig. 3. Fig. 8 is a section on the line 8—8 of Fig. 3.

Referring in the first instance to Figs. 1 and 2, *x* indicates the transom, which is hinged at the lower edge and above a door *y*, while *z* indicates the door-casing to which my lifter is applied.

The vertically slidable rod 1 is guided in a bracket 2, and a plate or ribbon spring 3, of due strength is secured to the upper end of the rod and serves as the means of direct connection between the rod and the transom 45 *x*. The lower end of the spring 3 is inserted in a cleft in the rod 1 and secured by a cross-pin, as shown in Fig. 3. The upper end of the spring is formed as a loop—see Fig. 3—and it is applied detachably to the 50 laterally bent arm 4 of a bracket having a base 5 which is screwed to the transom as shown in Fig. 1.

The bracket 2 may be formed of cast metal or of plate metal struck up in dies. 55 Its lower end is provided with screw-holes and its upper end with inwardly projecting

arms 2^a whose inner ends are bent at a right angle and provided with screw-holes for attachment of the bracket to the door-casing *z*, as shown in Figs. 1 and 3. The curved face 60 of the bracket is smooth save the three projections 2^b which are in the nature of loops adapted to hold and guide the spring 3 in its sliding movement. These loops may be preferably formed by striking up from the body of the bracket or they may be cast integrally therewith. As shown, the upper end of the bracket projects forward from the door casing, and therefore it also projects forward of the transom, as shown in 70 Figs. 2 and 3.

It is apparent that, by adjusting the rod 1 vertically upward, the spring will push against the arm 4 of the bracket attached to the transom and thereby throw the transom forward on its hinges, as shown by dotted lines in Fig. 2, thus opening the transom to a corresponding extent. As shown by dotted lines in said figure, the upper end of the spring describes a short curve when this adjustment is made. On the other hand, by pulling down on the rod 1, the spring will obviously draw the transom back to the closed position. This operation is easily effected, for the spring slides easily in the 85 bracket 2.

It will be understood that while I illustrate the transom as hinged at the bottom, it may be hinged at the top or pivoted at the middle, and my improved lifter may be applied to these forms with equal facility.

The means for adjusting the slidable rod 1 are as follows: The rod passes through a tubular rack 6—see Figs. 7 and 8—to which it is secured by a pin 7. This rack is 95 guided in a casing 8 that is provided with apertured lugs 9, as shown in Fig. 7, which are adapted to receive screws for securing it to the door casing *z*. A pinion 10—see Fig. 8—is pivoted in the casing 8 and meshes 100 with the rack 6. This pinion is mounted on a short polygonal shaft 11—see Figs. 3 and 6—which has its bearings in the casing 8 and also in the tubular shank 12 of a knob 13. Such shank is adapted to slide through an 105 opening in the front of the casing 8, and on its inner end is fixed a disk or collar 14—see Figs. 3 and 6—which disk is provided with pins 15 projecting from its outer side and adapted to enter holes 16 in the front 110 of the casing 8. A spiral spring 17 is arranged in the tubular shank of the knob 13

between the head of said knob and the short or stub shaft 11 and tends to press the knob outward so as to hold the disk pins normally engaged with the casing. The bore in the shank 12 of the knob is rectangular, so that the shaft 11 must rotate therewith. It will now be apparent that, normally, the pinion 10 is locked and thus holds the adjusting rod 1 fixed in any position to which it may be 5 adjusted, with the transom either closed, or open more or less. In order to adjust the rod and thereby the transom, it is necessary to push inward against the knob 13 and thus force it into the position indicated by dotted 10 lines in Fig. 3, such operation being of course resisted by the spring 17. By such adjustment, the locking disk 14 is freed from engagement with the casing 8 and thus the stub shaft 11 may be rotated as required. 15 20 In other words, when the knob is pressed inward and then rotated, the pinion 10 will adjust the rod 1 up or down as may be required to open or close the transom.

What I claim is:—

25 1. The combination with a hinged transom and a vertically adjustable rod, of a plate spring connecting them, a fixed guide for the spring, the same having a curved face and provided with means for holding the 30 spring to said face, as described.

2. The combination with a hinged transom

and a vertically slideable rod, of a spring connecting them, and a guide arranged intermediately of the transom and rod and consisting of a bracket having a curved face 35 and integral loops for holding the spring to the face, as described.

3. In a transom lifter, the guide for a spring forming part of said lifter, the same consisting of a bracket having a curved face 40 provided with means for holding the spring in its sliding movement, the bracket being also provided at the upper end with rearward projections adapted to be secured to a door casing, substantially as described. 45

4. The combination with a transom rack-rod, a pinion engaging it, and a casing inclosing them, of a polygonal shaft whereon the pinion is mounted, a knob having a hollow shank whose polygonal socket receives 50 the shaft, the inner end of the same having its bearing in the casing, a spiral spring arranged in the hollow shank and bearing against the knob and shaft, and a locking disk having outwardly projecting pins which 55 normally engage the casing when the spring is expanded the hollow shank being slideable in the casing and on the shaft, as described.

JOHN H. GARTNER.
